SWITCH POINT LOCK

Lawrence T. Ferguson, North Platte, Nebr.

Application May 20, 1938, Serial No. 209,108

4 Claims. (Cl. 246—448)

My invention relates generally to means for locking a switch point in closed position, and particularly to a switch point lock which cannot be opened except by proper operation of release mechanism, so as to remain closed even when struck by the passage of objects thereover, such as automobiles, at a crossing, or by objects on or thrown from a train passing thereover, and an important object of my invention is to provide a simple and efficient arrangement of this character.

Another important object of the present invention is to provide an arrangement of the character indicated which is small and compact and inexpensive to manufacture, and which can be installed in place in a comparatively few minutes.

Other important objects of my invention will be apparent from a reading of the following description taken in connection with the drawings, wherein for purposes of illustration I have shown a preferred embodiment of my invention.

In the drawings:

Figure 1 is a longitudinal sectional view taken through an embodiment of the invention and through the rail and the switch point related thereto.

Figure 2 is a top plan view of the embodiment per se.

Figure 3 is an enlarged transverse vertical sectional view taken through Figure 1 approximately on the line 3—3 and looking toward the left in the direction of the arrows.

Figure 4 is a perspective view of the locking element.

Figure 5 is a top plan view of the adjustable abutment.

Figure 6 is a perspective view of the slidable detent for the locking element.

Referring in detail to the drawings, the numeral 5 generally designates a rail having the web 6 supporting the head 7, and rising from the outer flange 8 and the inner flange 9, the said rail resting upon and being secured to a tie 10. An open topped casing 11 of generally rectangular form is secured by fastening means 13 to a part of the anchor which is generally designated 14 and which is connected to the rail 5, thereby enclosing all of the mechanism except the rod 27.

The anchor 14 has an elongated rectangular base 15 which is cut away at one end thereof as indicated by the numeral 16 to provide the bearing ears 17 and 18 which are traversed by a pivot bolt 19 which is locked in place with a nut 20. From the opposite end of the base 14 rises a short

standard 21 which abuts the edge of the flange 8 of the rail shown in Figure 1 and has leading from the top thereof the oblique portion 22 which rests on the slanting upper surface of the flange 8, from which portion 22 rises a second standard portion 23 which fits against the adjacent side of the web 6 of the rail and whose upper end is conformably shaped as indicated by the numeral 24 to engage the undersurface of the head 7 of the rail, the anchor thereby substantially conforming to the bottom of the rail and one side thereof in a manner to be securely and rigidly connected to and suspended by the rail 5. As shown in Figure 1 of the drawings the bifurcated end of the anchor base 15 extends beyond the inner flange 9 of the rail.

Bolted as indicated by the numeral 25 to the bottom of the right hand end of the base 15 is a bracket 26 which slidably supports the operating rod 27 which projects into the casing through an opening 28 formed in the end of the casing and connects with the slidable block 38 which is movable backwardly and forwardly on the track 36, the block 38 being located between the arms of the yoke 63, the opposite end of the rod 27 being connected with a turnbuckle 29 which, in turn, is connected to a bolt 30 which is pivoted as indicated by the numeral 31 to the lower end of a lever 32 which is pivoted at its upper end as indicated by the numeral 33 on a bracket 34 mounted on the upper part of the tie 10. The upper end of the lever 32 has a lateral arm 35 which is set at an upwardly inclined angle to provide mechanical advantage for operating the rod 27 to release the switch point lock by depressing the arm or lever 35.

Adjacent the bifurcated end of the base 15, the base 15 has attached to the bottom thereof a pair of laterally spaced channel guides 36, 37 which form a sliding support for the block 38 which is shown in detail in Figure 6 as comprising a generally rectangular block 39 through which extends from front to rear a threaded bore 40 which goes all the way through the block and receives the left hand end of the operating rod 27. The front end of the block is cut away as indicated by the numeral 41 to provide the shoulder 42. The upper end of the block is provided with opposite lateral flanges 43 and 44 for slidably engaging with the slide guides 36 and 37. The operating rod 27 has on its left hand end a collar 45 against which bears the left hand end of the expanding helical spring 47 which is circumscribed on the rod 27 between the collar 45 and the bracket 26, this spring thereby acting to keep the

block 38 engaged with the locking element to be described. In its relaxed position the left hand end of the spring 46 also bears against the yoke 63 thereby holding the block up in position. It is to be noted that the rod 27 is in an out of the way and protected position so that it will not easily be struck accidentally by any object as a result of the passage of a train over the switch or other cause.

10 The locking element which is generally designated 48 comprises a transversely elongated block 49 from one side of which projects an elongated arm 50 which is longitudinally traversed by a bore 51 which rotatably receives the pivot bolt 15 49 already alluded to. The arm 50 is of a size to conformably fit in the opening 16 in the base 15 of the anchor. The top of the block 49 is provided with ribs 52, and bolt holes 53 traverse this block to receive the bolts 54 and 55 which pass through elongated openings 57 and 58 which 20 traverse the abutment which is generally designated 56, the bottom of the abutment being provided with complementary ribs 59 for engagement between the ribs 52 on the top of the block 59 for engaging between the ribs 52 on the top of the block 49, the elongation of the holes 57 and 58 being provided to enable adjustment of the abutment 56 toward and away from the switch point. Depending from the bottom of the block 30 49 and the arm 50 is a rectangular cross section element 60 which is traversed by a bore 61 rotatably receiving the pivot bolt 62 which traverses the arms of a yoke 63, which yoke embraces also the detent 38, with the bight of the yoke 35 traversed by the rod 27, the said bight portion being located between the back of the detent and the collar 45 on the shaft 27. The end of the element 63 of the locking element is cut away as indicated by the numeral 84 and to provide 40 the horizontal surface 65 and the vertical surface, respectively, which are engaged, respectively, by the top surface of the cut away 42 of the detent 38 and the vertical surface of this cut away in the engaged position of the detent, with the locking element in the locking position.

45 Referring to Figure 1 of the drawings, the numeral 65 generally designates the switch point which is provided with a lateral projection 66 which when the switch point is in the closed position illustrated is very close to the abutment 56, so that the abutment acts to positively prevent the switch point from leaving the side of the rail 5. When it is desired to release the switch lock, by removing the abutment from holding relation 50 to the projection 66 of the switch point 65, the lever 35 is depressed so as to draw the operating rod 27 toward the right thereby compressing the spring 46 and pulling the detent 38 along its guides 36 and 37 out of engagement with the surfaces 65 and 66 of the element 60 of the locking element and into engagement with the bight of the yoke 63 thereby positively tilting the locking element away from the switch point 65 and allow opening of the switch point. It is to be observed that no pressure exerted by the switch point in an opening direction, is effective to open the switch point any more than is any inadvertent exertion of pressure on the switch, until the lock has been opened or released as described by operation of the pedal 35.

65 Although I have shown and described herein a preferred embodiment of my invention, it is to be definitely understood that I do not desire to limit the application of the invention thereto, and any change or changes may be made in the 70

materials and in the structure and arrangement of the parts, within the spirit of the invention and the scope of the subjoined claims.

Having described the invention, what is claimed as new is:

1. In combination, a switch comprising a stock rail and a switch point, a switch point lock comprising an anchor, means connected between said anchor and said stock rail and positively locking said anchor on said stock rail, a locking element pivoted on said anchor, an abutment on said locking element for engaging the switch point to hold the switch point closed, a detent movably mounted on said anchor and lockably engageable with a portion of said locking element only while said locking element is in operative position, and means connected with and normally holding said detent in operative position, said means comprising a spring pressed rod, operating means for moving said rod to a detent withdrawing position, and an operating connection between said locking element and said rod. 15

2. In combination, a stock rail, a switch point engageable with one side of said stock rail, an anchor mounted on said stock rail and extending along one side and across the bottom of said stock rail, a switch point locking element pivoted horizontally to said anchor at the switch point side of the rail, an abutment on said locking element normally engaging a portion of said switch point to hold the switch point closed, a movable detent mounted on said anchor and normally lockably engaging a portion of said locking element to hold the locking element in switch point holding position, means connected to and normally maintaining said detent in operative position, said means comprising a releasable member operable to withdraw said detent out of holding relation to said locking element, said means also having connection with said locking element to swing said locking element out of switch point holding position upon complete withdrawing operation of said means. 35

3. A lock for a switch, said switch comprising a stock rail and a relatively movable switch point, said lock comprising an anchor, means positively securing said anchor with portions thereof engaged with the bottom, the flange, and the web of said stock rail so as to be completely supported by said stock rail, a lock comprising a body pivoted on said anchor for swinging on a horizontal axis, said lock comprising an abutment arranged to lockably engage the side of the switch point in the erect operative position of the lock, said lock further comprising a projection extending under said anchor and formed with two differently angulated surfaces, a detent carried by said anchor above said projection and having two surfaces correspondingly angulated with respect to the first mentioned surfaces, means movably connecting said detent to said anchor to permit of moving said detent away from said projection to free the lock to permit tilting away from the switch point, said means permitting moving said detent to engage its two surfaces with the two surfaces of the projection only with the lock in its erect operative position whereby said lock is positively prevented from being tilted out of its erect switch point locking position, and a spring pressed rod connected to said detent for urging the detent toward locking engagement with said lock. 50

4. A lock for a switch, said switch comprising a stock rail and a relatively movable switch point, said lock comprising an anchor, means positively 55

securing said anchor with portions thereof engaged with the bottom, the flange, and the web of said stock rail so as to be completely supported by said stock rail, a lock comprising a body pivoted on said anchor for swinging on a horizontal axis, said lock comprising an abutment arranged to lockably engage the side of the switch point in the erect operative position of the lock, said lock further comprising a projection extending under said anchor and formed with two differently angulated surfaces, a detent carried by said anchor above said projection and having two surfaces correspondingly angulated with respect to the first mentioned surfaces, means movably connecting said detent to said anchor to permit of moving said detent away from said projection to free the lock to tilt away from the switch

point, said means permitting moving said detent to engage its two surfaces with the two surfaces of the projection only with the lock in its erect operative position whereby said lock is positively prevented from being tilted out of its erect switch point locking position, a spring pressed rod connected to said detent for urging the detent toward locking engagement with said lock, and a yoke pivotally connected to said lock and secured to said rod, whereby operation of said rod in one direction releases the detent from the lock and tilts the lock to an inoperative and movement in another direction tilts said lock to erect position and lockably engages said detent therewith.

LAWRENCE T. FERGUSON. 15
